UNITED STATES PATENT OFFICE.

JULIUS KOZORA, OF BROOKLYN, NEW YORK.

DUMPING-BUCKET.

No. 834,305.

Specification of Letters Patent.

Patented Oct. 30, 1906.

Application filed May 28, 1906. Serial No. 319,012.

To all whom it may concern:

Be it known that I, JULIUS KOZORA, a citizen of the United States, residing at Brooklyn, in the county of Kings and State of New York, have invented certain new and useful Improvements in Dumping-Buckets, of which the following is a specification, such as will enable those skilled in the art to which it appertains to make and use the same.

o This invention relates to dumping-buckets of the class used in hoisting dirt and other material from excavations by means of derricks, traveling trolleys, and similar devices; and the object of the invention is to provide improved means for dumping the contents of such buckets.

The invention is fully disclosed in the following specification, of which the accompanying drawings form a part, in which the separate parts of my improvement are designated by suitable reference characters in each of the views, and in which—

Figure 1 is a side view of a dumping-bucket constructed according to my invention and showing the bottom closed; Fig. 2, a view similar to Fig. 1, but showing the bottom open; Fig. 3, a view at right angles to that shown in Fig. 1, and Fig. 4 a plan view of the bucket as shown in Fig. 1.

o In the practice of my invention I provide a bucket *a*, which in the form of construction shown is substantially rectangular or square in cross-section, but which may be of any desired shape in cross-section, and said bucket may be composed of sheet metal or any suitable material and is preferably provided with a reinforcing top band *a*² and a reinforcing bottom band *a*³, and in the form of construction shown the bottom portion of the bucket is contracted, as shown at *a*⁴, and slightly smaller than the top portion thereof.

Hinged to the back of the bottom portion of the bucket, as shown at *a*⁵, is a bottom *b*, and said bucket is provided with a suspending-yoke *c*, the side portions of which are pivoted or hinged to the opposite sides of the bottom *b* and adjacent to the hinge *a*⁵ of said bottom, as shown at *c*².

The yoke *c* extends a predetermined distance above the bucket, and connected with the cross-head member *c*³ thereof is a link *d*, which is also connected with an ear *d*², secured to the top front portion of the bucket opposite the hinge of the bottom *b* at *a*⁵, and secured to the top front portion of the bucket below the ear *d*² is a spring *e*, which passes

downwardly below the bottom of the bucket and is provided with a catch-head *e*², which is adapted to engage the free edge of the bottom *b* of the bucket and hold it in a closed position.

The bottom *b* of the bucket comprises a plate *b*², secured to angle-iron side and back members *b*³, and secured to the bottom plate *b*² is a forwardly and backwardly ranging spring-plate *f*, which projects beyond the free edge of the bottom *b* and is provided with an aperture *f*², through which the head *e*² of the spring-arm *e* passes.

Secured to the side of the bucket to which the spring-arm *e* is secured is a keeper *g*, in which is pivoted an arm *h*, which ranges transversely of the body of the bucket back of the spring-arm *e*, and by means of which in the operation of dumping the bucket the head *e*² of the spring-arm *e* is disconnected from the free edge of the bottom *b* of the bucket and said bottom allowed to drop, as shown in Fig. 2.

The opposite sides of the bottom *b* of the bucket are also provided with reinforcing members *b*⁴, with which the sides of the yoke *c* are connected and which serve as means for hinging the bottom *b* at *a*⁵.

The top portion of the yoke *c* is arranged transversely of the center of the bucket; but the side arms of said yoke are inclined or curved backwardly, as shown at *c*⁴, and secured to the opposite sides of the bucket, and near the back thereof are stops *i*, which limit the movement of the bucket in the yoke *c* when the contents of the bucket are dumped or the bottom *b* of said bucket lowered, as shown in Fig. 2.

The operation will be readily understood from the foregoing description when taken in connection with the accompanying drawings and the following statement thereof. It will be understood, of course, that the hoisting-cable or other device is connected with the yoke *c* at *j* in the usual manner, and when the bucket has been filled and hoisted and moved to the dumping point or place the spring *f* is depressed by the attendant on the ground in order to permit the head *e*² of the spring *e* to be released from the bottom *b*, and the free end of the arm *h* is pulled outwardly and the lower end of the spring *e*, or the head *e*² thereof, is disconnected from the free edge of the bottom *b*, and the said bottom swings into the position shown in Fig. 2, and after the contents of the bucket have been dumped in

this manner a pull on the yoke *c* will automatically close the bottom *b*, as shown in Fig. 1. It will therefore be seen that the dumping of the bucket is produced by means 5 of the arm *h*, and the bottom *b* is automatically closed when the bucket is again raised and transported to the point at which it is to be refilled.

It will be understood that the operation of 10 this device depends upon the fact that the sides of the yoke *c* are pivoted to the opposite sides of the bottom *b* rearwardly of the vertical transverse center of the bucket or near to the hinges *a*⁵, whereby most of the 15 load on the bottom of the bucket is between the yoke pivots or hinges *c*² and the free edge of said bottom, and when said free edge of the bottom of the bucket is released, as hereinbefore described, the said bottom is forced 20 downwardly and the various parts swing into the position shown in Fig. 2.

Having fully described my invention, what I claim as new, and desire to secure by Letters Patent, is—

25 1. A dumping-bucket provided with a bottom which is hinged to said bucket at the back thereof, a suspending-yoke the sides of which are pivoted to the opposite sides of the bottom adjacent to the hinges thereof 30 and the cross-head of which extends above the bucket and is connected with the front top portion thereof by a link, and means for holding the hinged bottom in a closed position.

2. A dumping-bucket provided with a bottom which is hinged to said bucket at the back thereof, a suspending-yoke the sides of which are pivoted to the opposite sides of the bottom adjacent to the hinges thereof and the cross-head of which extends above the 35 bucket and is connected with the front top portion thereof by a link, and means for holding the hinged bottom in a closed position, comprising a spring-arm secured to the front 40

of the bucket and provided with a catch-head adapted to engage the free edge of the bottom when the latter is closed, and means for releasing said arm. 45

3. A dumping-bucket provided with a bottom which is hinged to said bucket at the back thereof, a suspending-yoke the sides of which are pivoted to the opposite sides of the bottom adjacent to the hinges thereof and the cross-head of which extends above the bucket and is connected with the front top portion thereof by a link, and means for holding the hinged bottom in a closed position, 50 comprising a spring-arm secured to the front of the bucket and provided with a catch-head adapted to engage the free edge of the bottom when the latter is closed, and means for releasing said arm, the opposite sides of the bucket being also provided near the back thereof with stops in connection with which the sides of the suspending-yoke operate. 55

4. A dumping-bucket provided with a bottom which is hinged thereto at the back thereof, a suspending-yoke the sides of which are pivoted to the opposite sides of the bottom adjacent to the hinges thereof, the cross-head of the yoke extending above the bucket, 60 a link connecting the cross-head of the yoke with the front top portion of the bucket, stops connected with the opposite sides of the bucket near the back thereof, and an automatic device adapted to engage the bottom 70 of the bucket when closed and hold it in a closed position. 75

In testimony that I claim the foregoing as my invention I have signed my name, in presence of the subscribing witnesses, this 26th 80 day of May, 1906.

JULIUS KOZORA.
